US0D1077581S

(12) **United States Design Patent** (10) Patent No.: **US D1,077,581 S**
Emirhanoglu et al. (45) Date of Patent: ** Jun. 3, 2025

(54) **PLATE**

(71) Applicant: **TURKIYE SISE VE CAM FABRIKALARI ANONIM SIRKETI, Istanbul (TR)**

(72) Inventors: **Basak Emirhanoglu, Istanbul (TR); Umut Sinan Karaca, Istanbul (TR)**

(73) Assignee: **TURKIYE SISE VE CAM FABRIKALARI ANONIM SIRKETI, Istanbul (TR)**

(**) Term: **15 Years**

(21) Appl. No.: **35/520,128**

(22) Filed: **Dec. 24, 2023**

(80) **Hague Agreement Data**

Int. Filing Date: **Dec. 24, 2023**

Int. Reg. No.: **DM/235317**

Int. Reg. Date: **Dec. 24, 2023**

Int. Reg. Pub. Date: **Mar. 1, 2024**

(30) **Foreign Application Priority Data**

Jul. 4, 2023 (TR) 2023/006524

(51) **LOC (15) Cl.** **07-01**

(52) **U.S. Cl.**

USPC **D7/562; D7/585; D7/624.1**
